UNITED STATES PATENT OFFICE.

RANSOM W. DAVENPORT, OF DETROIT, MICHIGAN, ASSIGNOR TO DETROIT STOVE WORKS, OF DETROIT, MICHIGAN, A CORPORATION OF MICHIGAN.

COMBINED COAL AND GAS RANGE.

1,213,846.

Specification of Letters Patent. Patented Jan. 30, 1917.

Application filed January 24, 1916. Serial No. 74,003.

To all whom it may concern:

Be it known that I, RANSOM W. DAVENPORT, a citizen of the United States of America, residing at Detroit, in the county 5 of Wayne and State of Michigan, have invented certain new and useful Improvements in Combined Coal and Gas Ranges, of which the following is a specification, reference being had therein to the accompanying drawings.

The invention relates to stoves designed for the alternative use of solid and gaseous fuel and the invention comprises various features of construction as hereinafter set 15 forth.

In the drawings, Figure 1 is a perspective view of the stove; Fig. 2 is a horizontal section therethrough; Fig. 3 is a transverse section; and Fig. 4 is an end elevation.

20 A is the oven, B is the fire-box having a flue extending across the top of the oven, C is an end flue and D is a bottom flue connecting with the rear flue E, the arrangement being common to stoves of this type.

25 The oven A is also provided with a swell or extension E' at the back thereof which is beyond the bottom flue D.

30 F is a gas burner which extends longitudinally of the oven within the swell E' and near the bottom thereof. This burner has forwardly-directed gas jets, and the flame therefrom is confined beneath a partition or false bottom G extending to the oven front.

35 With the construction as thus far described difficulty has been experienced in lighting the burner due to the formation of an explosive mixture of air and gas in the limited space between the oven bottom and

40 the partition G. Thus even where a lighter extending to the front is provided for the burner, before this lighter can become operative from gas delivered to the burner the explosive mixture will be formed which

45 will cause a puff or explosion of the gas. To overcome this difficulty I have provided a lighter operable from the front of the stove and which is supplied with gas in advance of the turning on of gas to the main burner. To insure this sequence of operation independent valves are provided for the lighter and main burner, and the valve controlling the former produces a lock pre-

venting the prior actuation of the burner valve. 55

In detail, H is the burner valve and I is the lighter valve, both of which are connected to a common gas supply conduit J arranged at the end and back of the stove. The handles for operating these valves are 60 preferably rods K and L extending to the front in a position for convenient operation.

M is a gas tube extending from the burner I into the oven and in position for coupling engagement with a lighter tube N which 65 latter is preferably secured to and beneath the removable partition G. Any suitable interlock is provided for compelling the actuation of the valve I in advance of that of the valve H, but as shown the stem K of the 70 valve I has mounted thereon a finger O which normally stands in the path of a finger P on the stem L of the valve H, the arrangement being such that the valve H may not be opened until the stem K has been 75 turned sufficiently to remove the finger O, which operation opens the valve I and supplies gas to the lighter. I also preferably provide a connection between the operating stem L of the burner valve H, which controls an air valve or damper Q in the oven back. This valve is normally closed when the gas is turned off, which prevents venting of the oven when operated by solid fuel, but whenever the gas burner valve is turned 80 on the damper Q is opened. This operation is effected by a rock-arm R on the stem L of the valve H, which on the opening movement of said valve engages a rock-arm S on the rock-shaft T which forms the hinge of 85 90 Q.

In operation when the stove is operated by solid fuel the partition G is removed and with it is removed the lighter tube N attached thereto, so that the entire oven 95 space is available for use. The damper Q is also closed to prevent any venting of the oven. When it is desired to employ the gaseous fuel the partition G is placed in the oven, which will engage the lighter tube N 100 with the gas tube M. The oven burner may then be lighted by first turning the handle or stem K of the valve I so as to supply gas to the lighter which may be ignited from the front. The stem L is then turned 105 to open the gas valve H which furnishes a

supply of gas to the burner F, and the lighter, the inner end of which is in proximity to said burner, will instantaneously light the same preventing any formation of explosive mixture of gas and air.

What I claim as my invention is:—

1. In a stove, an oven, a gas burner extending longitudinally of said oven at the rear thereof and adjacent to the bottom, said burner having forwardly-directed jet openings, a partition or false bottom engageable with said oven above said burner forming a limited space between the same and the oven bottom, and a lighter tube for said burner mounted on said partition and removable therewith.

2. In a stove, the combination with an oven having a swell or projection in the rear wall thereof, of a gas burner extending longitudinally in said swell and adjacent to the oven bottom, said burner having forwardly-directed jet openings, a partition or false bottom for the oven engageable therewith above said gas burner, and a lighter tube connected with said false bottom and removable therewith.

3. In a stove, the combination with an oven of a burner at the rear of said oven and adjacent to the bottom thereof, a removable partition or false bottom engageable with the oven above said burner, a lighter tube mounted on said partition and removable therewith, and a gas supply tube for said lighter registerable and engageable therewith upon the insertion of said partition.

4. In a stove, the combination with an oven, of a gas burner arranged at the rear

thereof and adjacent to the bottom, a false bottom engageable with said oven above said burner, a lighter tube mounted on said false bottom, a gas supply tube registerable and engageable with said lighter tube upon the insertion of said false bottom, and independent valves for controlling the gas supply to said lighter tube and burner.

5. In a stove, the combination with an oven, of a burner arranged adjacent to the bottom and at the rear thereof, a false bottom engageable with the oven above said burner tube, a lighter tube mounted on said false bottom, a gas supply tube registerable and engageable with said lighter tube upon the insertion of said false bottom, independent valves controlling the gas for said lighter tube and burner, and an interlock between said valves for compelling the opening of the lighter valve in advance of the burner valve.

6. In a stove, the combination with an oven, of a burner arranged at the rear and adjacent the bottom of said oven, a normally closed valve controlling an air vent into said oven adjacent to said burner, a lighter for said burner, independent valves for controlling the gas supply to said lighter and to said burner, an interlock between said valves compelling the opening of the lighter valve in advance of the burner valve, and means operating upon the opening of the burner valve for opening said vent damper.

In testimony whereof I affix my signature in presence of two witnesses.

RANSOM W. DAVENPORT
